UNITED STATES PATENT OFFICE.

RAYMOND H. MINNS, OF BEDFORD HILLS, NEW YORK.

SASH-HOLDER.

1,333,272.

Specification of Letters Patent.

Patented Mar. 9, 1920.

Application filed May 11, 1918. Serial No. 233,839.

To all whom it may concern:

Be it known that I, RAYMOND H. MINNS, a citizen of the United States, residing at Bedford Hills, in the county of Westchester and State of New York, have invented certain new and useful Improvements in Sash-Holders, of which the following is a specification, reference being had to the accompanying drawings.

10 This invention relates to an improved sash holder, and has for its primary object to provide a holder of that general type wherein a roller is employed for frictional wedging engagement with the window sash, which is of such construction that the upper and lower sashes of the window will be securely held against relative movement.

15 It is another object of my invention to provide a window sash holder, the several parts of which may be easily and quickly assembled in operative position, or disassembled when the use of the device is not desired or it is necessary to repair any of the parts.

20 And it is also an important object of my invention to provide a holder for window sashes which consists of few parts of very simple and durable construction, and can be quickly and securely mounted in operative position upon the sash rail without necessitating structural modifications in the latter.

25 With the above and other objects in view the invention consists in the improved combination, construction and arrangement of the several parts as will be hereinafter more particularly described, subsequently claimed and illustrated in the accompanying drawing in which similar reference characters designate corresponding parts throughout

30 the several views; and wherein:

35 Figure 1 is a perspective view, illustrating the preferred embodiment of my invention applied to a window sash;

Fig. 2 is a vertical sectional view;

40 Fig. 3 is a section taken on the line 3—3 of Fig. 2;

Fig. 4 is a side elevation illustrating the manner in which the parts of the device may be assembled or disassembled; and

45 Fig. 5 is a detail horizontal section taken on the line 5—5 of Fig. 4.

Referring in detail to the drawing, 5 designates generally a socket member which is preferably formed from a heavy sheet metal plate. The medial portion of this

plate at one of its ends constitutes the rear wall 6 of the socket member, and the side portions of the plate are bent to provide walls or flanges 7 extending at right angles to the plane of the wall 6 from the opposite edges thereof. The remaining body portion of the plate is bent inwardly from the upper end of the wall 6 between the spaced side flanges 7, and is obliquely extended as shown at 8 to the free vertical edges of said flanges where the inclined wall 8 has its terminal horizontally disposed as at 9. This terminal of the wall 8 is provided with an opening to receive the attaching screw 10. One of the side flanges 7 of the socket member is formed with an outwardly projecting ear 11 which is also apertured to receive an attaching screw 12.

50 The flanges or walls 7 of the socket member constitute confining means for a roller 13 and prevent lateral displacement of the roller. This roller consists of a heavy metal body or core upon the peripheral face of which a band of rubber or other yielding material indicated at 14 is suitably secured. 55 The opposite side faces of the metal body of the roller are preferably recessed or channeled as shown at 15 so that there will be a relatively small surface area of the roller having contact with the inner faces of the flanges 7. This materially reduces the possibility of the roller sticking or working sluggishly due to the collection of rust or dust between the roller faces and the flanges 7 so that no force other than gravity is necessary to maintain contact of the rubber surface 14 of the roller upon the face of the inclined wall 8 of the socket member. The core or body of the roller is further provided with an axially extending socket or 60 recess 16 opening upon one face thereof. The purpose of this socket will be presently explained.

65 One of the side flanges 7 of the socket member is formed with a keyhole slot having a circular end portion 17 and a relatively narrow horizontally extending portion 18. 19 designates an operating lever preferably curved as shown and having an angularly disposed terminal arm 20 adapted for loose 70 engagement in the recess 16 in the side face of the roller 13. The lever 19 is further provided upon one edge with a laterally projecting hook-shaped lug 21 and terminates at its other end in a suitable finger 75

piece 22. The lug 21 normally operates in the circular end 17 of the keyhole slot in the flanges 7.

In mounting the device in operative position, the socket member 5 is secured upon the top rail of the lower sash S as shown in Fig. 1 with its open side opposed to the vertical stile of the upper sash S'. The terminal of the inclined wall 8 and ear 11 are then securely fixed to the rail by means of the screws 10 and 12. The rubber surfaced roller disposed between the side flanges 7 of the socket member moves by gravity downwardly on the inclined wall 8 and against the stile of the upper sash. If an attempt is made to lower the upper sash or raise the lower sash, the surface of the roller is compressed and frictionally engaged tightly against the face of the sash 20 stile and the surface of the wall 8 of the socket member, and constitutes a wedge to effectively lock the sashes against relative movement. When it is desired to adjust the sashes for purposes of ventilation, the finger piece 22 of the lever 19 is depressed, thus throwing the roller upwardly and inwardly on the inclined wall 8 of the socket member and away from the surface of the stile of the upper sash. The sashes can then be readily adjusted to the desired positions and the roller again released so that the sashes will be securely held. By providing the attaching screws 10 located immediately beneath the wedging roller, the mounting of the socket member is greatly strengthened and the possibility of its displacement from the rail of the lower sash reduced to a minimum.

When it is necessary to repair the sashes 40 or paint them, the device may be readily removed from its applied position on the rail of the lower sash, and the several parts of the sash holder can also be easily disassembled when it becomes necessary to resurface the wedging roller or to make other repairs thereto. As shown in Fig. 4, when the device is removed from the sash rail the roller 13 will move to the lower end of the inclined wall 8 and rest upon the horizontal terminal 50 9 thereof. In this position of the roller, the angular end of the hook-shaped lug 21 of the lever will be slightly out of registering relation with the narrow horizontal portion 18 of the keyhole slot in the flange 7. However, by now exerting a downward pressure on the roller and compressing its yieldable surface 14 against the horizontal terminal 9 of the wall 8, the terminal of said lug may be disposed in full registration with the keyhole slot, and said lug withdrawn laterally through said slot whereby the lever may be detached from the flange 7. The wedging roller can then be removed from the socket member. Thus it will be apparent that 60 when the device is applied in operative posi-

tion it will be impossible for the several elements to become separated but such separation can be effected only by a positive operation as above stated.

From the foregoing description taken in 70 connection with the accompanying drawing, it will be seen that I have devised a very simple and durably constructed sash holder, and one which may be easily and quickly applied in its operative position without necessitating any alterations in the sash construction. The device can also be produced at 75 relatively small manufacturing cost and is highly efficient and serviceable in practical use.

While I have herein shown and described the preferred construction and arrangement of the several parts, it is to be understood that the device is susceptible of considerable modification therein and I therefore reserve 80 the privilege of adopting all such legitimate changes as may be fairly embodied within the spirit and scope of the invention as claimed.

I claim:—

1. A sash fastener including a socket member adapted to be secured to the top rail of the lower sash, said socket member having spaced flanges and an inclined wall extending downwardly between the flanges 95 toward the meeting rail of the upper sash, one of said flanges having a keyhole slot therein, a roller movable by gravity upon said inclined wall and against the stile of the upper sash, said roller having a surface 100 of yieldable friction material, and a lever operatively engaged at one of its ends with said roller and having a part extending through the keyhole slot to support the lever for pivotal movement relative to the socket member, said part preventing disengagement of the lever from the roller or the socket member in the normal position of the roller, the compression of the roller surface permitting of a movement of the lever 110 to dispose said part for movement through the keyhole slot whereby the lever may be disconnected from the roller and the socket member.

2. A sash fastener including a socket 115 member adapted to be secured to the top rail of the lower sash, said socket member having spaced flanges and an inclined wall extending downwardly between said flanges toward the meeting rail of the upper sash, 120 a roller provided with a peripheral surface of yielding material and movable upon said inclined wall into engagement with the stile of the upper sash, said roller having a central recess in one of its side faces, one of 125 said flanges having a keyhole slot therein, and a lever having an angular terminal loosely engaged in the recess of said roller and provided intermediate of its ends with an integral hook-shaped lug engaged 130

through the keyhole slot in said flange to support the lever for pivotal movement on the exterior of the socket member, the terminal of the hook-shaped lug being movable 5 into registration with the narrow portion of the keyhole slot upon the compression of the peripheral surface of the roller when the latter is in a predetermined position

whereby the lever may be disconnected from the socket member and the roller. 10

In testimony whereof I hereunto affix my signature in the presence of two witnesses.
